UNITED STATES PATENT OFFICE.

HENRY W. FISHEL, OF NEW YORK, N. Y., ASSIGNOR TO SAID HENRY W. FISHEL AND THEODORE H. FISHEL, OF NEW YORK, N. Y., COPARTNERS, TRADING AS FISHEL, NESSLER & CO.

DESIGN FOR A BROOCH-PIN.

No. 38,622.

Specification for Design.

Patented June 18, 1907.

Application filed April 29, 1907. Serial No. 371,021. Term of patent 14 years.

To all whom it may concern:

Be it known that I, HENRY W. FISHEL, a citizen of the United States, residing at the borough of Manhattan, in the city, county, and State of New York, have invented a new, original, and ornamental Design for Brooch-Pins, of which the following is a specification, reference being had therein to the accompanying drawing, forming a part thereof.

Figure 1 is a face view of a brooch pin showing my new design. Fig. 2 is a perspective view of the same.

I claim:

The ornamental design for a brooch pin as shown.

HENRY W. FISHEL.
